US0D1071149S

(12) **United States Design Patent** (10) **Patent No.:** **US D1,071,149 S**
(45) **Date of Patent:** **** Apr. 15, 2025**

(54) **SUCTION TOOL**

(71) Applicant: **ENTELLUS MEDICAL, INC.**, Maple Grove, MN (US)

(72) Inventor: **Alexander Houck**, Lino Lakes, MN (US)

(73) Assignee: **Stryker Corporation**, Portage, MI (US)

(**) Term: **15 Years**

(21) Appl. No.: **29/861,207**

(22) Filed: **Nov. 28, 2022**

(51) **LOC (15) Cl.** **24-02**

(52) **U.S. Cl.** **D24/112**
USPC .....

(57) **CLAIM**

The ornamental design for suction tool as shown and described.

DESCRIPTION

FIG. 1 is a perspective view of a suction tool showing my new design.

FIG. 2 is a first side elevation view of the suction tool of FIG. 1.

FIG. 3 is a second side elevation view of the suction tool of FIG. 1.

FIG. 4 is a third side elevation view of the suction tool of FIG. 1.

FIG. 5 is a fourth side elevation view of the suction tool of FIG. 1.

FIG. 6 is a bottom view of the suction tool of FIG. 1; and, FIG. 7 is a top view of the suction tool of FIG. 1.

The portions of the drawings shown in broken lines represent environmental aspects and form no part of the claimed design.

1 Claim, 4 Drawing Sheets
